UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

DOORWAY CONTROL OR GATE FOR USE IN RAILWAY CARS.

1,413,840.

Specification of Letters Patent. Patented Apr. 25, 1922.

Application filed March 21, 1921. Serial No. 454,031.

To all whom it may concern:

Be it known that I, THOMAS ELLIOTT, a citizen of the United States, residing at Cincinnati, in the county of Hamilton and State of Ohio, have invented certain new and useful Improvements in Doorway Controls or Gates for use in Railway Cars, of which the following is a specification, reference being had therein to the accompanying drawing.

This invention relates to improvements in doorway controls or gates for use in railway cars, such as cars used on city lines and interurban routes, these controls or gates being adjustable to permit the passengers to enter or to exit at a doorway remote from the one man or person operating the car.

To these ends the invention consists, essentially, of uprights carrying brackets provided with arms or guards held in normal position by spring devices which yield and permit the arms to swing open and return to closed position or to swing inward and return to such position, and of an adjustable sleeve having stops for controlling the position of the arms, whether such as to permit passengers to pass outward from the car or inward onto the car.

30 In the accompanying drawings;

Fig. 1 is an elevation of a portion of a railway car with my improved doorway controls or gates mounted therein;

Fig. 2 is a partial side elevation and sectional view, on an enlarged scale, showing the mechanism in detail;

Fig. 3 is a plan view of what is shown in Fig. 2;

Fig. 4 is a plan elevation of the controls or gates when adjusted in position for entering the car;

Fig. 5 is a similar view showing the controls or gates adjusted for leaving the car.

These gates or controls are located near the doorway of the car, say on the platform near the steps. This part of the platform is indicated at 1 in Fig. 1, with sockets 2 to receive the uprights 3, which are preferably in the form of tubes or pipes over 50 which are fitted sleeves 4, with filling blocks 5 between the upright or post 3 and the sleeve, collars 6 secured by pins 7 or otherwise on the upright serving to sustain the sleeves.

55 On the uprights 3 I mount a series of

arms 8 in the nature of bars of wood whose ends fit within brackets 9, as shown particularly in Fig. 2. These brackets 9 are mounted on the uprights 3 and have lugs 10 through which extend springs 11, 60 preferably in the nature of coiled springs, which extend also through the upright 3 and act to hold the arms in either the position shown in Fig. 4 for entrance into the car or that shown in Fig. 5 for exit from 65 the car, but which yield for the movement of the arms as passengers press against them in passing through.

The construction here described is duplicated in each of the brackets which respectively carry the several arms 8. It will be seen that the arms may swing inward for the admission of passengers, as indicated in Fig. 4, or may swing outward for the exit of passengers, as illustrated in Fig. 5. 75

Stops for positioning the arms and for limiting their movements are provided and constructed after this wise. About each upright 3 is placed the long sleeve 4, before referred to, and which sleeve is 80 mounted on the upright 3 in the manner before described. As shown in Fig. 3, the sleeve is cut away or open in that part through which the arms swing. At each side of the open space the sleeve is provided 85 with a rubber or other form of bumper 12 held in a holder 13. The sleeves are adjustable to the position shown in Fig. 4, which will permit the arms to swing inward for the entrance of passengers, or to 90 the position shown in Fig. 5 which will permit the arms to swing outward for the exit of passengers. For so adjusting the sleeves they are provided with crank arms 14, as seen more clearly in Fig. 4. These 95 crank arms are interconnected by a pitman 15, while an actuating rod 16 is employed to enable the motorman or man in charge of the car to adjust the arms 14 and therefore the sleeves 4 to either the position shown 100 in Fig. 4, in which the arms will open inward for the entrance of passengers, or to the position shown in Fig. 5, in which the arms will open outward for the exit of passengers.

105 In either case the bumpers 12 limit the swinging movements of the arms 8, the springs 11 acting to bring the arms back to either the position shown in Fig. 4 or that shown in Fig. 5, as the case may be. 110

It will now be understood that with my improved doorway controls or gates I can permit the passengers to enter the car, as when the arms are in the position shown 5 in Fig. 4, by merely pushing the arms apart as they pass in, or I can permit them to leave the car, as when the arms are in the position shown in Fig. 5, likewise by merely pressing the arms apart.

10 It will be seen that my improved controls or gates operate equally well for the admission of passengers, as for their exit, and that they also likewise operate to prevent the exit and entrance of passengers until 15 the proper adjustment has been made to that end.

Having thus fully described my invention, what I claim as new and desire to secure by Letters Patent, is:—

20 1. The combination, with a car doorway, of a doorway control comprising members and stops therefor, the members being adapted to swing apart as passengers pass in one direction, and to oppose the entrance of 25 passengers in the other direction, and mechanism to adjust said control members to positions to permit passengers to exit or enter.

2. The combination, with a car doorway, of uprights adjacent said doorway, a series 30 of arms mounted on said uprights and adapted to be adjusted to exit position or entrance position, and sleeves adapted to be adjusted to exit position or entrance position and to permit the outward movement of the arms in 35 the one and the inward movement of the arms in the other position.

3. The combination, with a car doorway, of uprights each carrying a series of brackets, spring devices for holding the brackets 40 in adjusted positions but permitting them to yield, arms carried by the brackets, a sleeve partially encircling each upright and having stops and adapted to be adjusted to permit the arms to open outwardly or inwardly.

45 4. The combination, with a car doorway, of an upright approximately at each side thereof, a series of brackets mounted on each

upright, springs to permit the brackets and arms to swing to and from closed position, and a sleeve for each upright adjustable to 50 move the arms to exit position or entrance position and to permit the arms to swing open and return when adjusted to either position.

5. The combination, with a car doorway, of an upright at either side thereof, a series 55 of brackets mounted on each upright, an arm carried by each bracket, spring devices for permitting each bracket and its arm to swing for opening and closing the doorway, a sleeve partially encircling each upright and having bumpers for each bracket to limit the swing thereof, and means to adjust the sleeves and thereby the brackets to entrance or exit position.

6. The combination, with an upright and a bracket mounted thereon, springs to permit the bracket to swing to and from a given position, an arm carried by the bracket, a sleeve partially encircling the upright and 70 having stops or bumpers between which the bracket may swing, the sleeve being adjustable to set the arm to entrance or to exit position and to permit it to operate in either position.

7. The combination, with a pair of sleeves, and means interconnecting them, of an upright within each sleeve, each upright carrying arms adapted to swing outward or inward according to the adjustment of the 80 sleeves, and spring devices to return the arms to normal position when swung therefrom.

8. The combination, with a pair of sleeves each having an arm, and a pitman interconnecting them to adjust the sleeves to different positions, of uprights within the sleeves, brackets on the uprights, an arm carried by each bracket, and spring devices to permit the arms to swing apart and return, the sleeves being adjustable to present the arms 90 to exit position or entrance position.

In testimony whereof, I affix my signature.

THOMAS ELLIOTT.
